UNITED STATES PATENT OFFICE.

WILLIAM C. SHINN, OF CHICAGO, ILLINOIS, ASSIGNOR TO CHICAGO CABINET LOCK CO., OF CHICAGO, ILLINOIS, A CORPORATION OF ILLINOIS.

LOCK.

Application filed April 24, 1922. Serial No. 556,256.

To all whom it may concern:

Be it known that I, WILLIAM C. SHINN, a citizen of the United States, and a resident of Chicago, in the county of Cook and State 5 of Illinois, have invented certain new and useful Improvements in Locks, of which the following is a full, clear, and exact description.

The invention relates to locks and more 10 particularly to cylinder locks in which plate tumblers are used.

The object of the invention is to provide improved means for pressing some at least 15 of the tumblers into operative position to render the lock more efficient.

The invention consists in the several novel features hereinafter set forth and more particularly defined by claims at the conclusion hereof.

20 In the drawings: Fig. 1 is a section of a lock embodying the invention, the tumblers and the spring for shifting them being shown in elevation. Fig. 2 is a horizontal section. Fig. 3 is a section on line 3-3 of 25 Fig. 2. Fig. 4 is a detail perspective of the spring.

A casing 9 is adapted to rotatably hold a cylinder or carrier 8 which may be connected to operate a lock in any suitable or well 30 known manner.

The carrier is provided with a slot 10 in which a series of plate tumblers 11 are mounted so they may slide transversely to bring their ends into the usual locking slot 35 in the casing, as well understood in the art.

Each tumbler is formed with a key slot 12 and with lugs or terminals 15 adapted to enter one of the locking slots in the casing 9 to lock the cylinder, and when held in 40 correct position by the key 13 to clear the casing and release the carrier for rotation.

Notches 16 are formed in one of the side margins of the plate tumblers 11 and the shoulders 17 at the ends of the slots are 45 adapted to be engaged by a spring for normally pressing the tumbler into operative position. The improved spring for performing this function is formed of suitable wire and comprises coils 18 and 19 which have 50 their outer terminals integrally connected, as at 20, and their inner terminals extended to form oppositely extending arms 21 and 22 to press the tumblers engaged thereby in opposite directions. For example, arm 21 will 55 exert pressure upon the upper ends of the

tumblers near the front of the carrier and press them upwardly while the arm 22 will engage a number of the tumblers adjacent the back of the carrier and press them downwardly. When a key of the proper shape 60 is inserted, it will operate the tumblers against the force of the spring-arms 21 and 22.

The invention exemplifies a plate tumbler lock with means by which a single spring 65 serves to operate different tumblers in opposite directions to render the lock efficient in use.

The invention is not to be understood as restricted to the details set forth, since these 70 may be modified within the scope of the appended claims, without departing from the spirit and scope of the invention.

Having thus described the invention, what I claim as new and desire to secure by Letters Patent, is:

1. In a cylinder lock, the combination of a rotatable carrier, plate tumblers slideable transversely in the carrier, and having one side notched to form opposing shoulders, 80 and a spring comprising a helical coil adjacent the notched side and longitudinal arms extending in opposite directions from the coil to engage different tumblers and press them in opposite directions. 85

2. In a cylinder lock, the combination of a rotatable carrier, plate tumblers slideable transversely in the carrier and having one side notched to form opposing shoulders, and a spring comprising a plurality of 90 helical coils adjacent the notched side of the tumblers and arms extending longitudinally in opposite directions to engage the shoulders of different tumblers and press them in opposite directions. 95

3. In a cylinder lock, the combination of a rotatable carrier having a pocket in one side thereof, plate tumblers slideable transversely in the carrier and provided with shoulders at one side, and a spring adjacent one side of the tumblers, provided with means for pressing some of the tumblers outwardly and comprising a coil held in said pocket. 100

4. In a cylinder lock, the combination of 105 a rotatable carrier having a pocket in one of its sides, plate tumblers slideable transversely in the carrier and provided with shoulders at one side, and a spring adjacent one side of the tumblers, extending longitu- 110

dinally of the carrier, provided with means engaging the shoulders for pressing some of the tumblers outwardly, and comprising a plurality of coils held in said pocket.

5 5. In a cylinder lock, the combination of a rotatable carrier having a pocket in one of its sides, plate tumblers slideable transversely in the carrier and provided with shoulders at one side, and a spring adjacent

one side of the tumblers, comprising a plurality of coils held in said pocket, and arms extending longitudinally of the carrier and engaging shoulders on different tumblers to press them outwardly in opposite directions.

Signed at Chicago, Illinois, this 5th day of April, 1922.

WILLIAM C. SHINN.
